UNITED STATES PATENT OFFICE.

ALBERT N. OTIS AND EDWARD H. HORSTKOTTE, OF SCHENECTADY, NEW YORK, ASSIGNEES TO GENERAL ELECTRIC COMPANY, A CORPORATION OF NEW YORK.

ELECTRIC BOILER.

Application filed December 27, 1924. Serial No. 758,469.

To all whom it may concern:

Be it known that we, ALBERT N. OTIS and EDWARD H. HORSTKOTTE, citizens of the United States, residing at Schenectady, in the county of Schenectady, State of New York, have invented certain new and useful Improvements in Electric Boilers, of which the following is a specification.

The present invention relates to electric boilers of the electrode type, that is, of the type wherein one or more electrodes dip into liquid contained in a casing and generate vapor by the passage of electric current through the liquid. The common application of such boilers is in generating steam from water and as a matter of convenience the invention is described as used for this purpose. It will be understood, however, that this is only by way of example and 20 that the boiler may be used for generating vapor from any desired liquid.

The object of the invention is to provide an improved electric boiler which is particularly well adapted for low voltages, that is, voltages of the order of 200 to 600 volts for example, and one wherein a maximum of electrode surface is secured in a given size shell. In this connection it is known that for efficient results the current density must not exceed a certain amount and also that for voltages of a low order, the electrode surfaces become quite close together. This means, then, that to obtain a large output from current of comparatively low voltage, 35 electrodes having large surfaces arranged comparatively close together must be provided.

For a consideration of what we believe to be novel and our invention, attention is 40 directed to the accompanying description and the claims appended thereto.

In the drawing, Fig. 1 is a side elevation, partly in section of an electric boiler embodying our invention, and Fig. 2 is a section taken on line 2—2, Fig. 1, the invention being shown as being embodied in an electric boiler of the general type of that shown in the patent to Merrill and Winne, No. 1,462,350, July 17, 1923.

50 Referring to the drawing, 3 indicates a boiler shell having a lower head 4 and an upper head 5. On lower head 4 are suitable feet 6 for supporting the boiler. 7 is an opening in the upper end of shell 3 and

through which the steam generated in the 55 boiler is withdrawn. Inside the boiler adjacent to but spaced from its lower end is a supporting ring 8 upon which rests the arms of a spider 9. Carried by spider 9 are bottom and top walls 10 and 11 and 60 a side wall 12 which form a liquid chamber 13. Communicating with liquid chamber 13 at the center of spider 9 is a conduit 14 connected to the discharge side of a pump 15, the suction side of the pump being connected by a conduit 16 to the lower end of shell 3. At the bottom of head 4 is a sump 17 from which water may be drawn off and connected to shell 3 adjacent its lower end is a conduit 18 through which 70 water may be supplied to the boiler.

Mounted on top wall 11 at its peripheral edge is an inner shell 19 which stands in spaced relation to shell 3. When assembled spaced walls 10 and 11, side wall 12 and 75 inner shell 19 form in substance an integral structure which is somewhat in the form of a basket, wall 10 being the bottom of the basket and wall 11 being a false bottom which provides the liquid chamber 13. 80

Mounted on wall 11 inside inner shell 19 and in spaced relation to shell 19 and to each other are a plurality of triangular shaped filler members 20, three such filler members being shown in the present instance. The outer walls of fillers 20 are curved to conform to the curvature of inner shell 19 while the other two walls are straight. Located between filler members 20 are additional filler members 21 which are 85 attached directly to upper wall 11 and shell 19. Filler members 21 have flat sides which extend parallel to the flat sides of filler members 20. There are thus provided a number of radially-extending chambers 22 between 90

filler members 20 and 21 which chambers are connected to each other at their radially outer ends by arcuate chambers 23. At their inner ends chambers 22 open into each other. Arranged in chambers 22 are straight rectangular electrodes 24 which are supported from the adjacent walls of filler members 20 and 21 by suitable insulated pins 25, and supported in arcuate chambers 23 are rectangular curved electrodes 26 which are supported by the concentric walls of filler members 20 and inner shell 19 by suitable insulated supporting pins 27. Connected to 95 100 105

electrodes 24 and 26 are electrical conductors 28 which lead to connectors 29 fastened in boiler shell 3 by suitable insulators 30. All the connectors 29 may be connected to the 5 same phase of a single phase circuit in which case the several electrodes form the positive element of the boiler and the filler members 20 and 21, the inner shell 19, and the outer shell 3 form the negative element 10 of the boiler.

Viewed from one aspect, the chambers 22 and 23 may be considered as forming triangular shaped electrode chambers, in each 15 leg of which is an electrode. The chambers within filler members 20 and 21 do not form 20 parts of the active electrode chambers, that is, they do not contain liquid which carries electric current between electrodes. For this reason, such clearances may be termed inactive chambers.

The chambers 22 and 23 in which electrodes 24 and 26 are located are connected to liquid chamber 13 by holes 31 formed in wall 11 whereby liquid may flow from chamber 13 through holes 31 to chambers 22 and 25 23. In the side walls of filler members 20 and 21 are a number of holes 32 arranged in different vertical planes and through which water in electrode chambers 22 and 23 may 30 flow to the interiors of filler members 20 and 21. The water flowing into the space within filler members 20 flows back to the bottom of shell 3 through passages 33 which transverse liquid chamber 13 and the water 35 which flows into the spaces within filler members 21 flows back to the lower end of shell 3 through openings 34 formed in inner shell 19.

In operation there is a suitable supply of 40 water in the lower end of shell 3, the level of the supply being below supporting ring 8. Pump 15 operates to convey water from the lower end of shell 3 through conduits 16 and 14 to liquid chamber 13 from which 45 chamber it is forced up into the electrode chambers 22 and 23 through the openings 31. From electrode chambers 22 and 23 water runs back continuously through openings 32, 33 and 34 to the bottom of shell 3. 50 The size of openings 32 are such that water can flow through them at a predetermined rate so that the level of the water in the electrode chambers will depend on the rate at which pump 15 supplies water through conduit 14. The input to the boiler depends upon the extent to which the electrodes are submerged so that it will be clear that by increasing the rate of pumping the input to the boiler can be increased since the electrodes will be submerged further, while by decreasing the rate at which the pump supplies water through conduit 14 the input to the boiler can be decreased because of the fact that electrodes will not be submerged 55 so far.

This is the type of electric boiler control which is set forth in the aforementioned patent to Merrill and Winne.

The driving means for pump 15 is not illustrated in the drawing but it will be understood that any form of driving means such as an electric motor, for example, may be provided and that it may be controlled in any suitable manner.

The electric current passes from the electrodes 24 and 26 through the water to the inner shell 19 and to the filler members 20 and 21, thereby heating the water and generating steam which is led off through conduit 7.

Viewed from one aspect, the chambers 22 and 23 may be considered as forming triangular shaped electrode chambers, in each leg of which is an electrode. The chambers within filler members 20 and 21 do not form parts of the active electrode chambers, that is, they do not contain liquid which carries electric current between electrodes. For this reason, such clearances may be termed inactive chambers.

By the above-described arrangement it will be seen that there is provided electrode surfaces of considerable area which surfaces are comparatively close together whereby the boiler is adapted for comparatively low voltage and large output. At the same time the space within the boiler is utilized to the highest degree so that the shell may be made comparatively small for a given output.

In accordance with the provisions of the patent statutes, we have described the principle of operation of our invention, together with the apparatus which we now consider to represent the best embodiment thereof, but we desire to have it understood that the apparatus shown is only illustrative and that the invention may be carried out by other means.

What we claim as new and desire to secure by Letters Patent of the United States, is:

1. In an electric boiler, the combination of a shell, walls in the shell which form a plurality of radially-extending, spaced electrode chambers, electrodes in the electrode chambers, and means for supplying liquid to the electrode chambers.

2. In an electric boiler, the combination of a shell, spaced triangular shaped fillers in the shell which define electrode chambers, electrodes in the electrode chambers, and means for supplying liquid to the electrode chambers.

3. In an electric boiler, the combination of a shell, walls in the shell which form a plurality of spaced electrode chambers between which are inactive chambers, electrodes in the electrode chambers, means for supplying liquid to the electrode chambers, and means for conveying liquid from the electrode chambers to said inactive chambers.

4. In an electric boiler, the combination of a shell, walls in the shell which form a plurality of spaced electrode chambers between which are inactive chambers, electrodes in the electrode chambers, a source of liquid supply, and means for circulating liquid from the liquid supply through said

electrode chambers and said inactive chambers back to the liquid supply.

5. In an electric boiler, the combination of a shell, walls in the shell spaced from the bottom of it, said walls forming a plurality of spaced electrode chambers between which are inactive chambers, electrodes in said electrode chambers, means for supplying liquid from the bottom of the shell to said 10 electrode chambers, and means forming passages for conveying liquid from said electrode chambers through said inactive chambers back to the bottom of the shell.

6. In an electric boiler, the combination 15 of a shell, walls in the shell which define a plurality of radially-extending, circumferentially-spaced electrode chambers connected at their outer ends by arcuate shaped electrode chambers, electrodes in said electrode chambers, and means for supplying 20 liquid to said electrode chambers.

7. In an electric boiler, the combination 25 of a shell, triangular shaped filler members in the shell arranged in spaced relation to the shell and to each other whereby there

are formed a plurality of electrode chambers, electrodes in said electrode chambers, and means for supplying liquid to said electrode chambers.

8. In an electric boiler, the combination 30 of a shell, triangular shaped filler members in the shell arranged in spaced relation to the shell and to each other whereby there are formed a plurality of electrode chambers, said chambers being spaced from the 35 bottom of the shell, and means for circulating liquid from the bottom of the shell through said electrode chambers and back to the bottom of the shell again.

9. In an electric boiler, the combination 40 of a shell, walls in the shell which define a plurality of triangular shaped electrode chambers, electrodes in said electrode chambers, and means for supplying liquid to the electrode chambers.

In witness whereof we have hereunto set 45 our hands this 26th day of December, 1924.

ALBERT N. OTIS.
EDWARD H. HORSTKOTTE.
